(57) **CLAIM**

The ornamental design for an over the door towel rack, as shown and described.

DESCRIPTION

FIG. 1 is a front, left, and top perspective view of an over the door towel rack, showing my new design;

FIG. 2 is a rear, right, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the over the door towel rack that form no part of the claimed design.
